UNITED STATES PATENT OFFICE

ELDRIDGE M. BEECHER, OF NEW BRITAIN, CONNECTICUT

POLE REINFORCEMENT

Application filed October 3, 1929. Serial No. 397,020.

My invention relates to a pole reenforcement, and more particularly to a reenforcement suitable for use in reenforcing wooden poles such as those used for the support of electrical conductors, telephone and telegraph wires, and the like.

The useful life of a telegraph pole or the like is generally measured by the time required for the butt of the pole to rot, the 10 rotting proceeding much faster near the surface of the ground, owing to the fact that the pole is subjected to greater changes in moisture at this point. The replacement of a pole is rather expensive and quite often 15 poles having rotted bases are reenforced by two or more metallic members set in the earth alongside the pole and tightly clamped thereto.

In my co-pending application, filed 20 August 22, 1927, Serial No. 214,681, I have disclosed a pole reenforcement presenting a substantially smooth exterior surface on which there are no projecting parts, this reenforcement being adapted to be set into 25 the ground alongside the butt of a pole and to be clamped or secured tightly thereagainst to strengthen the pole. In my prior application, rods are shown for clamping the reenforcing member to the pole, the ends of 30 the rods passing through the reenforcing member and being received within pockets formed in the walls thereof, there being nuts on the ends of the rods in the pockets which may be reached from the exterior of the 35 member in order to tighten the latter against the pole.

The present invention relates to a reenforcing member of somewhat the general character of that disclosed in my co-pending 40 application and means is provided for clamping the member rigidly against the pole, the clamping means being carried generally within the contours of the member, the latter presenting a substantially smooth 45 exterior surface so that there is little, if any, tendency for a passing vehicle or the clothing of a pedestrian to be caught on the reenforcing member, as is the case with prior 50 pole reenforcements which are provided with projecting bolt ends, webs, and the like.

Generally speaking, the present invention is an improvement over my co-pending application, particularly with regard to the means for clamping the reenforcing member against the exterior surfaces of the pole.

As object of the invention is to provide a form of clamping means which may be carried within the general contours of the reenforcing member and by means of which the member may be readily and quickly 55 clamped against the surface of the pole.

To these and other ends, the invention consists in the novel features and combination of parts to be hereinafter described and claimed.

In the drawings,

Fig. 1 is an elevational view of a pole having reenforcing members according to my invention mounted on opposite sides thereof;

Fig. 2 is a side view of the reenforcing member shown in Fig. 1;

Fig. 3 is a cross-sectional view taken along the line 3—3 of Fig. 1, but on an enlarged scale;

Fig. 4 is a cross-sectional view taken along line 4—4 of Fig. 1, but on an enlarged scale;

Fig. 5 is an interior view of the upper end of one of the reenforcing members, the clamping means being removed;

Fig. 6 is a cross-sectional view taken along line 6—6 of Fig. 2, but on an enlarged scale;

Fig. 7 is a cross-sectional view similar to Fig. 6, but showing a modification; and

Fig. 8 is a fragmentary view of a reenforcement showing the modification of Fig. 7.

Referring to the drawings in which I have shown a preferred embodiment of my invention, the reference numeral 10 indicates, in general, a pole which, although broken away, will be understood to extend upwardly to any desired height and having a butt extending a substantial distance below the surface 11 of the earth.

Arranged on opposite sides of pole 10 are reenforcing members 12 and 13, each of which is provided with longitudinally

directed preferably parallel side walls 14 and 15 connected at their outer edges by a transversely extending wall 16, walls 14, 15 and 16 forming a hollow shell substantially U-shaped in cross-section throughout its length, with the opposite walls 14 and 15 forming the legs of the U, the terminal edges 17 and 18 of walls 14 and 15 bearing against the surface of the pole. The upper ends of the outer walls of the re-enforcing members 12 and 13 curve inwardly as at 19 and 20, to form relatively flat upper ends, for a purpose to be hereinafter described. The lower ends of reenforcing members 12 and 13 curve inwardly, as at 21 and 22, and thence outwardly, as at 23 and 24, so that when the reenforcing members are driven into the ground alongside the pole the lower ends tend to move towards and tightly embrace the butt of the pole.

Arranged at suitable intervals throughout the length of the reenforcing members are inwardly facing pockets 25, 26, 27 and 28 into which preferably flexible metallic straps 29, 30, 31 and 32 pass from the exterior of the reenforcing member, walls 14 and 15 being provided with openings 33 and 34, the side walls of pockets 25, 26, 27 and 28 being provided with openings 35 through which the straps pass. At the bottom of each of the pockets 25, 26, 27 and 28 are lugs 36 having sockets 37 in which the lower ends of dogs 38 are received, dogs 38 having their inner faces bearing against straps 29, 30, 31 and 32 and being provided on their opposite sides with a plurality of notches or indentations 39 in which key members 40 may be received to hold the dogs tightly in place. Opening to the exterior of reenforcing members 12 and 13 through walls 16 and into the pockets 25, 26, 27 and 28 are substantially T-shaped openings 41, 42, 43 and 44, the upper ends of these openings providing for the ready introduction of keys 40, and the lower of these openings providing for the introduction of a pinch bar or crow-bar, the lower end of which may be brought to bear against the inner surface of wall 16, as at 45, and against the dogs 38, at 46, to force the latter inwardly against the straps 29, 30, 31 and 32. If desired, the reenforcing members may be reinforced by one or more longitudinally directed webs 47 and transverse webs 48.

One or more reenforcing members 12 or 13 may be driven into the ground alongside a pole in a position where they bear tightly against the pole. When used in this manner, the reenforcing members 12 and 13 provide a convenient means for driving, while the relatively thin inwardly curved lower portion of the members tends to force the members towards the pole, or

the earth around the pole may be loosened enough so that the pole may be withdrawn, or a hole excavated around the pole to the depth to which the clamping means for the members is to extend. In any case, the reinforcing members are assembled on the pole in proper relation to the weakest portion thereof, or in other words, to that portion of the pole which is opposite the surface of the earth, whereupon the straps 29, 30, 31 and 32 are threaded through the openings 33, 34 and 35.

Dogs 38 are inserted through openings 41, 42, 43 and 44, the lower ends of the dogs resting in the sockets 37, while the inner faces thereof bear against straps 29, 30, 31 and 32. Key members 40, which in this instance are of rod-like form, are now introduced through the upper ends of T-shaped openings 41, 42, 43 and 44, whereupon a crow-bar or pinch bar is introduced successively in openings 41, 42, 43 and 44 and brought to bear against the inner surface of wall 16 at 45, and then against the dogs 38 at 46 to force the latter inwardly against the straps 29, 30, 31 and 32. As the straps 29, 30, 31 and 32 are drawn through openings 33 and 34 by the action of the dogs 38 thereon, they bind against the reenforcing members 12 and 13 and force them against the surface of the pole 10 which they tightly embrace. Upon inward movement of dogs 38, key members 40 are received successively in the notches 39 and bear against the inner surface of wall 16 to hold the dogs against outward movement away from the straps.

In Figs. 7 and 8 I have shown a modification in which the rod-like keys 40 are replaced by balls 49 introduced through openings 50 in walls 53, balls 49 being adapted to be received in sockets 51 in dogs 52 and to bear against the inner surfaces of walls 53, the latter being unbroken from opening 50 to the opening 54, which not only serves for the introduction of the dogs 52 into the reenforcing member but permits the introduction of the end of a pinch bar to force the dogs against the straps.

From the above description of my invention, it will be readily seen that I have provided a reenforcing member for a telegraph pole or the like presenting a substantially smooth outer surface with no projecting parts, and which may be readily and quickly clamped against the side of a telegraph pole or the like, the clamping means being locked securely in place.

While I have shown and described a preferred embodiment of my invention, it will be understood that it is not to be limited to all the details shown, but is capable of modification and variation within the spirit of the invention and the scope of the appended claims.

What I claim is:

1. In a pole reenforcement, a hollow member adapted to be set into the ground alongside the pole, a strap-like member embracing the pole and extending into the interior of the hollow member, and means carried in the interior of said hollow member and bearing against the strap at one side thereof for placing said strap under tension to clamp the hollow member to the pole. 5
2. In a pole reenforcement, a hollow member adapted to be set into the ground alongside the pole, a strap-like element embracing the pole and extending into the interior of the hollow member, a dog supported in said member for movement towards said strap to draw the member against the pole. 15
3. In a pole reenforcement, a hollow member adapted to be set into the ground alongside the pole, a strap-like element embracing the pole and extending into the interior of the hollow member, a dog supported in said member for movement towards said strap to draw the member against the pole, and means for holding said dog against movement away from the strap. 25
4. In a pole reenforcement, a hollow member adapted to be inserted into the ground alongside the pole, a strap-like member adapted to embrace the pole and extending into the interior of said hollow member, a dog supported in said hollow member for pivotal movement towards said strap, and means for holding said dog against movement away from the strap. 35
5. In a pole reenforcement, a hollow member adapted to be inserted into the ground alongside the pole, a strap-like element embracing the pole and extending into said member, and means carried in the interior of said member and bearing against the strap intermediate the ends thereof to place the strap under a variable tension to clamp the hollow member to the pole, said hollow member being provided with an opening extending to the exterior thereof through which an instrument may be inserted to actuate said means to vary the tension in the strap. 45
6. In a pole reenforcement, a hollow member adapted to be inserted into the ground alongside the pole, a strap-like member adapted to embrace the pole and to extend into said hollow member, a dog supported in said member for movement towards said strap to draw the member against the pole, and a key cooperating with said dog to hold the latter against movement away from the strap-like member. 55
7. In a pole reenforcement, a hollow member adapted to be inserted into the ground alongside the pole, a strap-like member embracing the pole and extending into said hollow member, a dog supported in said member for movement towards said
- strap, and a key cooperating with said dog to hold the latter against movement away from said strap-like member, said hollow member being provided with an opening through which the key may be inserted into the interior thereof. 70
8. In a pole reenforcement, a hollow member adapted to be inserted into the ground alongside the pole, a strap-like member embracing the pole and extending into said hollow member, a dog supported in said member for movement towards said strap, and a key cooperating with said dog to hold the latter against movement away from said strap-like member, said hollow member being provided with an opening through which said dog may be inserted into the interior thereof. 75
9. In a pole reenforcement, a member adapted to be inserted into the ground alongside the pole, a strap embracing the pole and extending into said hollow member, a dog supported on said hollow member for movement towards said strap, said member being provided with a socket in which the lower end of the dog is received, and means cooperating with the upper end of the dog for holding the latter against movement away from the strap-like member. 80
10. In a pole reenforcement, a member adapted to be inserted into the ground alongside the pole, a strap embracing the pole and extending into said hollow member, a dog supported on said hollow member for engaging said strap, said member being provided with a socket in which the lower end of the dog is received, means cooperating with the upper end of the dog for holding the latter against movement away from the strap-like member, a socket in which the lower end of the dog is received, the upper end of the dog being provided with a plurality of recesses and said means engaging the recesses to hold the dog in a plurality of positions relatively to the strap. 95
11. In a pole reenforcement, a member adapted to be inserted into the ground alongside the pole, a strap-like member embracing the pole and extending into the member, and means mounted on the hollow member for pivotal movement towards said strap to draw the member against the pole. 100
12. In a pole reenforcement, a hollow member adapted to be set in the ground alongside of the pole, a strap-like member embracing the pole and extending into the interior of the hollow member, and means supported upon said hollow member and movable toward said strap for placing the strap under tension to clamp the hollow member to the pole. 105
13. In a pole reenforcement, a hollow member adapted to be set into the ground alongside of the pole, a strap-like member 110

embracing the pole and extending into the interior of the hollow member, and means mounted on the wall of said hollow member for movements towards said strap to place the latter under tension.

- 5 14. In a pole reenforcement, a hollow member adapted to be set into the ground alongside of the pole, a strap-like member embracing the pole and extending into the interior of the hollow member, and a pressure member within said hollow member adapted to press against said strap to place it under tension and means to hold said pressure member against the strap.
- 10 15. In witness whereof, I have hereunto set my hand this 1st day of October, 1929:

ELDRIDGE M. BEECHER.
